UNITED STATES PATENT OFFICE

FRANK DAVIDSON AND ROUGHEN GUINN, OF ASHER, OKLAHOMA

WELL PLUG

Application filed December 29, 1930. Serial No. 505,427.

This invention relates generally to oil well apparatus and particularly to a salt water plug for plugging a well at any desired point which will admirably exclude salt water and will maintain the said salt water below the level of the plug.

My invention comprises various features of novelty and advantage which will be more clearly understood as the description proceeds, which provide conveniences of operation, manufacture and mechanical perfection not heretofore achieved in the art.

The object of the invention, its nature, its composition and arrangement and combination of parts will be readily understood by anyone acquainted with the art to which this invention relates upon consulting the following description and the drawings in which:

Figure 1 is a general elevational view of our device;

Figure 2 is an enlarged vertical transverse sectional view of the upper part of Figure 1, with the expanding plates expanded,

Figure 3 is a horizontal transverse section-al view taken on the line approximately 3-3 of Figure 2.

Figure 4 is an enlarged fragmentary cross sectional view of the lower portion of the device not disclosed in Figure 2 and

Figure 5 is a transverse horizontal cross section approximately on the line 5-5 of Figure 4.

Figure 6 is a detail transverse cross section-al view of the lower portion of Figure 2,

Figure 7 is an elevational view of the lower slip pin and its weight.

Figure 8 is an elevational view of the upper slip pin or wedge pin.

Figure 9 is a perspective view of the ex-tending plate.

Figure 10 is a perspective view of the lower slip support.

Referring in detail to the drawings, the numeral 5 designates generally a tubular casing having a bore 6 extended from its upper end downwardly to an intermediate portion thereof and where it is enlarged as indicated at 7 and cut away on two sides as shown at 8. The upper end of the upright tubular body 5 is formed with a laterally ex-

tending flange 9 on which is disposed a set of expanding plates adapted to be expanded by a wedge pin generally designated 11 which has the enlarged head 12, the conical wedge portion 13 and the reduced uniformly cylindrical portion 14 which projects in the bore 6 and through the enlargement 7 where it is engaged at its sides by a slip ratchet structure 15 which is urged by a spring 16 of the helical type circumposed about the reduced portion 14 of the wedge pin. The upper portion of the enlargement or chamber 7 is formed dome like as indicated at 17 and to cooperate with the rounded upper portions of the slip structure 15 whereby, whenever the wedge pin is moved downwardly the slip structure 15 will positively prevent the upward movement of the wedge pin. As described the lower end of the wedge pin moves in an axial continuation of the bore 6 and denominated 6a. The tapered portion 13 of the wedge pin cooperates with a tapered bore 18 formed in the expanding plates and also in a pair of lead gaskets 19 placed above the expanding plates.

Below the bore 6a there is formed an axial recess 20 which communicates with a tapered screw threaded receptor 21 in which is screw threaded by means of a nipple 22 a downwardly tapered wedge block 23, which has an axial centralized bore 24. Slidable in slots or guides 25 formed about the periphery of the wedge block 23 are tapered slips 26 having the teeth 27 for engaging the walls of the casing of the well. The slips 26 are vertically carried by pivoted links 28 upon a slip support 29 which has a general hexagonal shape disclosed in Figure 10. The slip support is provided with a hole in its center denomi-nated 30 and a notch cut straight inwardly 90 from the middle portion of each of its sides or as shown in the drawings in every other side. The notches are designated 31, and the sides are drilled as at 32 to provide for pivot pins for pivotally mounting the links in the 95 manner shown in Figure 1.

Adapted to have axial motion through the bore 24 of the wedge block 23 and through the hole 30 of the slip support 29, where it is secured by a cross pin 33 so as to provide 100

for moving the slip support 29 whenever it is moved, there is provided a lower or bottom slip pin 34 which has a disk head 35 on its upper end and a hole 36 in its lower end.

- 5 Within the recess 30 there is provided a coiled expansion spring 37 which normally presses the head 35 upwardly against the terminus of the recess 20, whereby the pin 34 is urged upwardly upon any slackening of a rope or cable 38 at the lower end of which is attached a conical or wedge shaped weight 39, whereby the lower slips 26 will be forced to climb the inclined faces of the guides of the wedge block, whereby they are forced outwardly to engage the interior wall of the well casing, for locking the plug therein.

The use and operation of the device is believed to be clear, since it is well known that devices of this type are to be used when drilling a well and reaching an oil level beyond which it is desired to drill, with a consequent discovery of a water level and a subsequent decision to cut off the water and break the casing at the first discovered oil level. The 20 device of my invention is lowered into the well and allowed to travel down in the casing until the weight 39 strikes the bottom of the well and forces the expanding of the lower slips 26 which firmly grip the interior 25 of the casing and prevent the upward movement of the plug. Upon driving the wedge pin 11 downwardly the expanding plates are forced against the wall of the casing and the lead gasket effectively prevents the escape of 30 water or gas beyond the said plug, the wedge pin being held against escape by the upper slip structure 15.

The features of novelty and the advantages of our invention will now be obvious 40 to anyone acquainted with the art to which this invention relates, and it is believed that its simplicity, cheapness of manufacture and high efficiency and ruggedness will be readily recognized.

- 45 It is to be definitely stated that we do not desire to limit the application of this invention to the particular modification set out herein to illustrate the principle thereof, and any change or changes may be made consistent with the spirit and scope of the invention.

Having thus described our invention, what we claim as new is:

1. A well plug of the type described comprising an upright body having a centrally and longitudinally formed upper bore extending from its upper end to an intermediate point, and a tapered and screw threaded lower bore extending from its lower end to a point below the lower terminal of the upper bore, an expansible body on the upper end of the body and a wedge pin movable in the upper bore for expanding said expansible body, and gripping means for the pin movable in a portion of said upper bore for limiting the upward movement of the pin, and an

expansible jaw structure on the lower end of the body, and means associated with the lower end of the body for expanding said jaw structure.

2. A well plug of the type described comprising an upright body having a centrally and longitudinally formed upper bore extending from its upper end to an intermediate point, and a tapered and screw threaded lower bore extending from its lower end to a point below the lower terminal of the upper bore, an expansible body on the upper end of the body and a wedge pin movable in the upper bore for expanding said expansible body, and gripping means for the pin movable in a portion of said upper bore for limiting the upward movement of the pin and an expansible jaw structure on the lower end of the body, and means associated with the lower end of the body for expanding said jaw structure, said means for expanding said expansible body on the upper end of the body comprising a tapered portion on said wedge pin, said expansible body having a tapered bore adapted to be acted upon by the tapered portion of the pin.

3. A well plug of the type described comprising an upright body having a centrally and longitudinally formed upper bore extending from its upper end to an intermediate point, and a tapered and screw threaded lower bore extending from its lower end to a point below the lower terminal of the upper bore, an expansible body on the upper end of the body and a wedge pin movable in the upper bore for expanding said expansible body, and gripping means for the pin movable in a portion of said upper bore for limiting the upward movement of the pin, and an expansible jaw structure on the lower end of the body, and means associated with the lower end of the body for expanding said jaw structure, said means for expanding said expansible body on the upper end of the body comprising a tapered portion on said wedge pin, said expansible body having a tapered bore adapted to be acted upon by the tapered portion of the pin, said gripping means comprising spring positioned jaws contained in an enlargement of the upper bore for engaging the lower end of the wedge pin.

4. A well plug of the type described comprising an upright body having a centrally and longitudinally formed upper bore extending from its upper end to an intermediate point, and a tapered and screw threaded lower bore extending from its lower end to a point below the lower terminal of the upper bore, an expansible body on the upper end of the body and a wedge pin movable in the upper bore for expanding said expansible body, and gripping means for the pin movable in a portion of said upper bore for limiting the upward movement of the pin, and an expansible jaw structure on the lower end of the

body, and means associated with the lower end of the body for expanding said jaw structure, said means for expanding said expansible body on the upper end of the body comprising a tapered portion on said wedge pin, said expansible body having a tapered bore adapted to be acted upon by the tapered portion of the pin, said gripping means comprising spring positioned jaws contained in an enlargement of the upper bore for engaging the lower end of the wedge pin, said expansible structure comprising a wedge block having guide grooves in its face and toothed jaws pivotally mounted on a support and 15 slidable in said grooves.

5. A well plug of the type described comprising an upright body having a centrally and longitudinally formed upper bore extending from its upper end to an intermediate point, and a tapered and screw threaded lower bore extending from its lower end to a point below the lower terminal of the upper bore, an expansible body on the upper end of the body and a wedge pin movable in the upper bore for expanding said expansible body, and gripping means for the pin movable in a portion of said upper bore for limiting the upward movement of the pin, and an expansible jaw structure on the lower end of the 20 body, and means associated with the lower end of the body for expanding said jaw structure, said means for expanding said expansible body on the upper end of the body comprising a tapered portion on said wedge pin, said 25 expansible body having a tapered bore adapted to be acted upon by the tapered portion of the pin, said gripping means comprising spring positioned jaws contained in an enlargement of the upper bore for engaging the 30 lower end of the wedge pin, said expansible jaw structure comprising a wedge block having guide grooves in its face and toothed jaws pivotally mounted on a support and slidable in said grooves, said means for 35 expanding the jaw structure comprising a weighted pin for moving said support upwardly upon contacting the weighted pin with the bottom of the well.

40 In testimony whereof we affix our signatures.

50 **FRANK DAVIDSON.**
ROUGHEN GUINN.
